SPRAY FOR FORMING A GARLAND

Kung Ping Chang, Kowloon, Hong Kong, assignor to Zunino Altman, Inc., New York, N.Y., a corporation of New York

Filed Mar. 4, 1963, Ser. No. 73,788

Term of patent 14 years

(Cl. D29—1)

FIG. 1 is a face view of a spray for forming a garland, showing my new design;

FIG. 2 is an edge view thereof;

I claim:

The ornamental design for a spray for forming a garland, substantially as shown.
